T. ODELL, SIDNEY SMITH, AND N. W. GODBOLD, ALL OF DALLAS, TEXAS.

WAGON-BRAKE.

SPECIFICATION forming part of Letters Patent No. 258,445, dated May 23, 1882.

Application filed January 25, 1882. (No model.)

To all whom it may concern:

Be it known that we, CHARLES JEROME LE ROY, of Palestine, in the county of Anderson and State of Texas, and JOHN WESLEY HENSON, of Dallas, in the county of Dallas and State of Texas, have invented a new and useful Improvement in Wagon-Brakes, of which the following is a full, clear, and exact description, reference being had to the annexed drawings, forming part of this specification.

The object of this invention is to provide an automatic brake for wagons and other wheeled vehicles running on dirt roads.

In the accompanying drawings, Figure 1 is a plan view of the running-gear of a wagon, showing our improved brake. Fig. 2 is a side elevation of a wagon with bed, showing the improvement, both views being partly broken away.

The reach *a* and hounds *b* of the wagon are provided with a cross-bar, *a'*, upon which is supported, in a horizontal position, the brake-arm *b'*. The brake-arm is connected to the rear bolster, *c*, by rods *c'* near the outer ends of said arm, and is connected by means of a rod, *d*, at the center with a lever, *d'*, pivoted to the under side of the reach. The long end of the lever is connected to the hound *b*, adjacent thereto, by a spiral spring, *e*, which tends to draw the said end rearward, while the said long end is also connected by means of a chain, *e'*, with the double-trees *f*. The double-trees are supported loosely upon the tongue *f'*, and confined within a guide consisting of the slotted bar *g*, secured longitudinally above the tongue by bolts at each end, which project above the bar. The double-trees are provided with an upward-projecting bolt, which plays within the slotted bar and prevents the double-trees from lateral movement. The double-trees are thus adapted to slide backward and forward along the tongue, and by means of a link, *g'*, in their bolt, which is to be hooked over the forward bolt of the slotted bar, may be held in a forward position, or by means of the link *g''* in the rear bolt of the slotted bar, which is to be hooked over the bolt of the double-trees, may be held in a rearward position.

The operation of the device is as follows: When power is applied to the double-trees 50 they slide forward under the slotted bar and draw the chain *e'*, which causes the short end of the lever *d'* to move backward. By this movement the brake-arm *b'* is forced upward by its connection with said lever and the 55 brake-shoes are held out of contact with the wheels. When going down grade, or when power is no longer applied to the double-trees, the tension of the spring *e* will cause the double-trees to slide backward and allow the 60 short end of the lever *d'* to move forward and draw the brake-arm *b'* downward until the shoes touch the wheels, when the friction of the latter will cause the shoes to move farther downward and bind the wheels. This result 65 is accomplished by the eccentric movement of the brake-arm, which moves along an arc having the center of its circle at the rear ends of the rods *c'*.

This brake may be used on a wagon either 70 with or without a bed, and when a bed is used it may be secured thereto by means of straps *i*, as shown in Fig. 2.

By means of the link *g'* the brake may be locked out of contact with the wheels, or by 75 the link *g''* it may be locked so as to hold the wheels as long as desired.

As the shoes in this brake are easily detachable, they may be removed in muddy lands to prevent clogging the wheels with mud. 80

Having thus described our invention, what we claim, and desire to secure by Letters Patent, is—

1. In a wagon-brake, the combination, with a running-gear, of a brake-arm supported 85 across the reach and connected by rods to the rear bolster, a lever pivoted underneath the reach and connected rigidly at one end to the said arm and at the other end having a spring connected to the adjacent hound, and a back-and-forth-sliding double-tree connected to said lever by a chain, substantially as shown and described.

2. In a wagon-brake, the combination, with a wagon, of the brake-arm *b'*, supported upon 95 the bar *a'*, the rods *c'*, connecting the arm to

the rear bolster, the lever d' , pivoted to the reach and connected to the arm by the rod d , the spring e , connecting the long end of the lever to the adjacent hound, and a suitable device for operating the said lever, substantially as shown and described.

3. In a wagon-brake, the combination, with a wagon, of the double-tree f , having an upward-projecting bolt provided with a link, g' , the guide consisting of the slotted bar g and

upward-projecting bolts at each end, and the link g^2 in the rear bolt, and a suitable brake connected to the double-tree, substantially as shown and described.

CHARLES JEROME LE ROY.
JOHN WESLEY HENSON.
